UNITED STATES PATENT OFFICE.

WILLIAM B. BARY, OF ST. PETERSBURG, RUSSIA.

MEANS FOR MAKING METALS DENSE IN LIQUID STATE.

964,371.

Specification of Letters Patent. Patented July 12, 1910.

Application filed August 16, 1909. Serial No. 513,175.

To all whom it may concern:

Be it known that I, WILLIAM B. BARY, a citizen of the United States of America, and a resident of St. Petersburg, Russia, my post-office address being Isaac's Place, 7, have invented certain new and useful Improvements in Means for Making Metals Dense in Liquid State, of which the following is a specification.

10 My invention relates to means for casting ingots and other articles in rotating molds, and has for its object the production of such articles in a quick and expeditious manner, while at the same time causing the metal 15 through the action of centrifugal force to be increased in density and to be freed from slag, gases and other impurities.

With these ends in view, the invention consists in the novel details of construction 20 and combinations of parts more fully hereinafter disclosed and particularly pointed out in the claims.

Referring to the accompanying drawings forming a part of this specification in which 25 like letters refer to like parts in all the views:—Figure 1 represents a vertical sectional view, taken on the line A—B in Fig. 2, of an apparatus suitable for carrying out my invention; Fig. 2, is a plan view of the 30 parts shown in Fig. 1; Fig. 3, is a sectional view of said parts taken on the line C—D of Fig. 2; Fig. 4, is a plan view of a modified structure suitable for casting pipe; Fig. 5, is a vertical sectional view of the parts shown 35 in Fig. 4, taken on the line G—H—I in Fig. 4; Fig. 6 is a sectional view taken on the line E—F, of Fig. 7, of a further modification suitable for casting strips of metal of various cross sections; and, Fig. 7, is a plan 40 view of the parts shown in Fig. 6.

Referring to Figs. 1 to 3, a suitable masonry foundation is shown to which is secured as by the bolts W a foundation plate provided with suitable anti-friction balls 45 V, on which rests the lower end of a shaft u, the upper end t of which carries a suitable support to which is secured by bolts the rotating horizontally disposed disk or wheel p, provided with the vertical ring like rim S 50 having the horizontally inturned edge e, and an extended outer edge on which rests the ring r surrounding the rim S, as shown. A circular hollow channeled plate x is supported in the masonry and fitted with the 55 anti-friction balls y, against which takes the outer rim of the disk p, as illustrated.

Supported by the disk p and held down from vertical movement by the inturned edge e are a plurality of box like, preferably tapered molds a disposed along the radii 60 of the disk p, and having their enlarged open ends disposed near the center of said disk. Between these molds are a plurality of sector shaped wedges d, which prevent the sidewise movement of the molds and 65 above their inner ends are the sector shaped wedges f which securely hold said ends from rising, as will be readily understood. These wedges f are firmly bound together by the band K, the ends of which are 70 detachably secured together, as illustrated in Fig. 2. A tapered refractory lined pipe provided with a channel c occupies the center and is secured to the disk p as shown; and leading through the refractory bricks g into 75 the open ends of the molds a, are the channels i which also connect with the channel c.

m represents spaces for the escape of gases etc., between the open ends of the molds and the bricks g.

The operation of the apparatus so far described is as follows: The metal is poured and enters the molds a through the channels c and i, while the disk p and molds are given a very rapid rotation through any suitable means, not shown. During this rotation the band r prevents the rim S from breaking under the enormous centrifugal strains to which it may be subjected, and the band K prevents the wedges f from leaving their positions. In the mean time the molten metal is forced toward the outer closed ends of the molds a and there compacted so to speak, or rendered more dense under the action of the centrifugal force to 90 which it is subjected. This force in tending to move the heavier metal particles radially outward and also by displacement causes the lighter particles of slag to move in toward the center, thereby freeing the metal from 95 its impurities, while at the same time any gases that may be disengaged by this action may escape through the spaces m. After the molds a have received their allotted quantity of metal the rotation of the disk p 100 is increased in order to obtain better results while the metal is hardening, and this rotation is kept up until the metal assumes a dull red color. After the metal has cooled, 105 some of the wedges d and f are removed, 110 the molds a lifted from the disk p and their ingots extracted.

Referring now to the structure disclosed in Figs. 4 to 7, similar masonry is provided, with bolts w and a foundation plate u' carrying the anti-friction balls r' on which rests the shaft S' having a support on which is secured the disk a' provided with the annular groove i' and the wedges d' rigid with said disk. The outer edge of the disk a' takes against a plurality of balls t' held in the groove of a suitable circular plate u'' secured to the masonry, while in the circular groove i' fit a plurality of ring sections f' , between which are wedges h' to hold them in place. In this form of my invention, the molds b' are radially disposed, as illustrated, but as shown to the left in Fig. 5 with their partially closed ends located near the center of the circle instead of near its circumference. The open ends of these molds are closed by the ring sections f' , and the metal enters through the passages m' connecting with the passages c' , while the gases pass out of the passages l' shown in dotted lines in Fig. 4 which communicate with the said inner ends of said molds. e' represents ring sections for securely holding the outer ends of the molds in place, while g' represents slots through the vertical rim of the disk a' to permit the removal of the ingot or mold when desired. K' represents a core in the mold for making pipe. The operation of this pipe casting mechanism is the same as that above disclosed and need not be here repeated, beyond stating that the bell end of the pipe which is outward will be rendered more dense and freer from impurities through the action of centrifugal force, than would be the case if no such force was called into action. An important advantage exists, however, in this form of my invention, over the first form, in the fact that the molds may be stripped by simply pulling out the wedge h' , shifting the sections f' so as to uncover the ends of the molds, and then after the runners and sprues are severed a slight rotation of the disk will force the molded article through the opening g' . This action permits the operation to be practically continuous for only the runners and bricks n' need be removed, when the molds are again closed and metal allowed to enter.

Referring now to Figs. 6 and 7, wherein is shown a means for casting strips of metal; the same general construction as that above is disclosed. The metal enters the passage c'' at the center of the rotating disk; flows along the passage a'' in the brick m'' ; and enters the circular mold cavity b'' , Fig. 6, of any desired cross sectional shape. As the metal rises in the cavity b'' , the gases escape through the upper passages d'' located above the upper portion l'' of the brick runners m'' . When the metal appears in this last mentioned passage, the pouring is

stopped, but the rotation of the disk is continued until the metal is quite hard, when the wedges f'' are withdrawn, and the annular parts g'' between the halves l'' of the brick runners m'' , are removed; whereupon said halves l'' may be withdrawn. 70

The clamping ring i'' is removed as well as the sector plates K'' , when the molded circular strips may be severed from the sprues and removed from the mold. They 75 are then straightened in suitable rollers and are ready for use.

In all the forms it will be observed that there is present the same general principle of compacting, purifying and rendering 80 more dense the metal through the action of centrifugal force. Therefore, it is evident that those skilled in the art may vary the details of construction and arrangement of parts without departing from my invention 85 and I do not desire to be limited to such details except as may be required by the claims.

What I claim is:

1. In an apparatus for molding articles, 90 the combination of a disk adapted to be rotated; a vertical rim carried by the other portion of said disk; a central shaft on which said disk is mounted; an anti-friction bearing for the outer edge of said disk; 95 comprising a circular plate having a channel and anti-friction balls in said channel; suitable molds supported by said disk; means located at the center of said disk for admitting metal to said molds; means comprising wedges for readily attaching said molds to and detaching them from said disk; additional wedges for separating said molds and holding them in place and means for permitting the escape of gases from said 100 molds after the metal is poured and said disk begins to rotate; substantially as described. 105

2. In an apparatus for casting articles, the combination of a rotating disk; a plurality of radially disposed molds carried thereby; wedges for separating said molds and holding them in position; a circular groove in the outer portion of said disk to which the open ends of said molds extend; 110 and ring sections in said groove for closing said molds; substantially as described. 115

3. In an apparatus for casting articles, the combination of a rotating disk; a plurality of radially disposed molds carried thereby; wedges for separating said molds and holding them in position; a circular groove in the outer portion of said disk to which the open ends of said molds extend; ring sections in said groove for closing said 120 molds; wedges between said ring sections; and means located centrally of said disk for admitting metal to said molds; substantially as described. 125

4. In an apparatus for casting articles, 130

the combination of a rotating disk; a plurality of radially disposed molds having an open and a closed end carried thereby; a circular groove in said disk above which the open ends of said molds are located; ring sections fitting said groove and closing said molds; wedges separating said sections; wedges separating said molds; a central passage for molten metal; branch passages between the closed ends of said molds and said central passage; and openings *g* in said disk through which the contents of said molds may be discharged; substantially as 25
10 sages between said molds and said central passage; substantially as described.

5. In an apparatus for casting articles, the combination of a rotating disk; a plurality of radially disposed molds having an open and a closed end carried thereby; a circular groove in said disk near which the open ends of said molds are located; ring
15

sections fitting said groove and closing said molds; wedges separating said sections; wedges separating said molds; a central 20 passage for molten metal; branch passages between the closed ends of said molds and said central passage; and openings *g* in said disk through which the contents of said molds may be discharged; substantially as 25 described.

In testimony whereof, I have signed my name to this specification in the presence of two subscribing witnesses.

WILLIAM B. BARY.
